Primary Examiner—Nelson C. Holtje*Assistant Examiner*—Jeffrey Asch*Attorney, Agent, or Firm*—Veal & Associates[57] **CLAIM**

The ornamental design for a display rack for boxed merchandise and the like, as shown and described.

DESCRIPTION

FIG. 1 is a perspective view of a display rack for boxed merchandise and the like showing my new design;
FIG. 2 is a front elevational view thereof;
FIG. 3 is a rear elevational view thereof;
FIG. 4 is a side elevational view thereof, the side not shown being a mirror image of the side shown;
FIG. 5 is a top plan view thereof;
FIG. 6 is a bottom view thereof;
FIG. 7 is a side elevational view of the present invention supporting a plurality of boxes which are shown in broken lines to illustrate environmental structure and which form no part of the claimed design; and,
FIG. 8 is a perspective view of the present invention reconfigured to an alternate position for use.
